B. P. JOYCE

PORTABLE WINCH

Filed Sept. 6, 1923

UNITED STATES PATENT OFFICE.

BRYAN P. JOYCE, OF DAVENPORT, IOWA, ASSIGNOR TO THOMAS A. CONLON, OF SILVER SPRING, MARYLAND.

PORTABLE WINCH.

Application filed September 6, 1923. Serial No. 661,268.

(GRANTED UNDER THE ACT OF MARCH 3, 1883; 22 STAT. L. 625.)

To all whom it may concern:

Be it known that I, BRYAN P. JOYCE, a citizen of the United States, and a resident of Davenport, county of Scott, and State of Iowa, have invented an Improvement in Portable Winches, of which the following is a specification:

The invention described herein may be used by the Government, or any of its officers or employees in prosecution of work for the Government, or by any other person in the United States, without payment to me of any royalty thereon, in accordance with the act of March 3, 1883.

The present invention relates to portable winches and particularly to that type of hoisting device used for moving a gun on and off its carriage for transport purposes.

The primary object of this invention is the provision of such means which may be actuated by a member or members of the gun crew and which through the intermediation of differential gearing will effect any desired reduction or change in direction between the hoisting mechanism and the actuating means therefor.

Another object is the provision of a hoisting device which will be compact in form and cheap of manufacture.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a view in side elevation of my hoisting device;

Fig. 2 is a section on the line 2—2 of Fig.

45 1; and

Fig. 3 is a section on the line 3—3 of Fig. 2.

Referring to the drawing by numerals of reference:

50 I have shown at 5 a winch having a projection 6 which fits in a slot formed in a sup-

porting bracket 8 for securing the winch in position on a transport wagon or limber.

The winch is formed by side plates 9 and 10 mounted on a shaft 11. The plate 9 through the projections 6 is firmly anchored against rotation on the support. The plate 10 is rotatably mounted on the shaft 11 for a purpose hereinafter to be described. The shaft 11 may be rotated in the usual manner by a crank or cranks, not shown.

In the preferred embodiment of my invention the plate 10 is provided with an annular flange 12 formed with a groove 13. A hoisting element such as a rope or chain 14 is provided which is adapted to be wound in said groove for elevating the gun from its cradle.

The hoisting element may be attached to the winch in any suitable manner. In practice I have found it preferable to line the groove 13 with a fabric strip 15 of high frictional coefficient such as a piece of brake lining. A few turns of the rope or chain 14 are taken about the groove and the friction of the brake lining with the rope or chain serves to maintain same in position.

The plates 9 and 10 cooperate to form a hollow housing or drum which houses the gearing by means of which the winch is rotated.

This gearing may be of any desired form. In the preferred embodiment the shaft 11 has a pinion 16 affixed thereto, which pinion meshes with three gears 17 squared on shafts 18 journaled in a housing 22 mounted between the plates 9 and 10. The gears 17 mesh with an annular gear 19 fixed to the plate 9. Keyed to the shafts 18 are other gears 20 meshing with an annular gear 21 fixed to the plate 10.

By using different speed ratios the rope or chain may be wound on the winch at a greater or less speed than that at which the shaft 11 is rotated or may be wound on said winch in a different direction from that taken by the shaft 11 in its movement. Collars 23 are secured to either end of the shaft 11 to maintain the members in their assembly and a plate 24 secured to the plate 9 serves as a dust guard.

In use one end of the rope 14 is attached

to the gun trail and the winch actuated to wind the rope on the flange 12 and lift the trail. When the slides of the gun carriage are brought to the same level with the slides 5 on the transport wagon, the gun may be readily slid off its carriage for transport. While particularly adapted for this use, it is obvious the winch of this invention is capable of employment in many other ways 10 as a hoisting device.

I claim:

1. In a portable winch, a rotatable shaft, a fixed plate in which said shaft rotates, a second plate rotatably mounted on said 15 shaft, a flange on said second plate, said plates cooperating to form a housing, annular gears secured to said plates respectively, a pinion affixed to said shaft, a gear mounted in said 20 housing and meshing with said pinion and one of said annular gears, a second gear actuated by said first named gear and meshing with the other of said annular

gears, the members of said gear train cooperating to transmit rotation of said shaft in a different phase to said second named plate, 25 said flange formed with a peripheral groove, a hoisting element adapted to be wound in said groove and means for securing said hoisting element to said housing.

2. In a portable winch, a rotatable shaft, 30 a fixed plate in which said shaft rotates, a second plate rotatably mounted on said shaft, a flange on said second plate, said plates cooperating to form a housing, annular gears on the respective plates, a pinion 35 affixed to said shaft, a gear mounted in said housing and meshing with said pinion and with one of said annular gears, a second gear actuated by said first named gear and meshing with the other of said annular 40 gears, the members of said gear train cooperating to transmit rotation of said shaft in a different phase to said second plate.

BRYAN P. JOYCE.
